ATTORNEY

UNITED STATES PATENT OFFICE

169,457

WRIST WATCH CASE OR SIMILAR ARTICLE

Ernest G. Schwarz, Forest Hills, N. Y.

Application October 23, 1952, Serial No. 21,950

Term of patent 3½ years

(Cl. D42—8)

To all whom it may concern:

Be it known that I, Ernest G. Schwarz, a citizen of the United States and a resident of Forest Hills, N. Y., have invented a new, original, and ornamental Design for a Wrist Watch Case or Similar Article, of which the following is a specification, reference being had to the accompanying drawing, forming a part hereof, in which

I claim:

The ornamental design for a wrist watch case or similar article, as shown.

ERNEST G. SCHWARZ.
